UNITED STATES PATENT OFFICE.

ERNEST E. DE BURGER, OF INDIANAPOLIS, INDIANA, ASSIGNOR OF ONE-HALF TO
BURTON E. WHITE, OF CINCINNATI, OHIO.

FILING-CASE.

1,242,101.

Specification of Letters Patent. Patented Oct. 2, 1917.

Application filed June 26, 1916. Serial No. 105,979.

To all whom it may concern:

Be it known that I, ERNEST E. DE BURGER, a citizen of the United States, and a resident of Indianapolis, county of Marion, 5 and State of Indiana, have invented a certain new and useful Filing-Case; and I do hereby declare that the following is a full, clear, and exact description thereof, reference being had to the accompanying drawings, in which like letters refer to like parts.

The object of this invention is the attainment of greater convenience in filing and handling record cards and the like, and increasing the capacity so as to reduce the 15 size of cabinets for filing such record cards.

The chief feature of the invention consists in having vertically disposed plates or frames slidable horizontally into and out of a suitable cabinet, said plates or frames 20 having on both sides thereof a pair of vertical guides to receive transverse resilient card holding strips which are easily put into and removable from the guides of said plates and when in the guides rest upon each 25 other and close together and are arranged so as to place one or more cards on each card holding strip so that the cards when filed will be arranged in a vertical series with the upper edges of the cards exposed 30 for showing the indicating names or data on the cards, while the main portion of each card will extend down behind the next lower card so that the main data or matter on the card will not be exposed.

35 The full nature of the invention will be understood from the accompanying drawings and the following description and claims:

In the drawings, Figure 1 is a front elevation of the device centrally and vertically broken away and with the right-hand portion in vertical section. Fig. 2 is a vertical section on the line 2—2 of Fig. 1, with one card holding panel drawn outward and a 40 part of the guideway being shown in section. Fig. 3 is a horizontal section on the line 3—3 of Fig. 2 with a part broken away and a part shown in altered position by dotted lines.

45 There is a cabinet casing 10 having a bottom, top, back and two sides with the front adapted to be open. In the bottom and top there are grooves or guideways 11 extending from the rear wall to the front,

but closed at the front by the flanges 12, as 55 shown in Fig. 2.

A card holding panel 13 is provided, one for each pair of grooves 11 and is a metal plate, as shown in Fig. 3, and vertically disposed and at its lower and upper rear 60 corners has secured to it vertically extending pivot pins 14 which project and move in said grooves 11, as seen in Fig. 2, whereby the panel 13 can be slid back and forth into and out of the casing 10. The bottom and 65 top of the casing extend somewhat farther forward than the side walls thereof, as shown in Figs. 2 and 3, so that when one of the panels 13 is drawn outward to its limit, as in said figures, it can be swung 70 around laterally, if desired, in either direction, to the right or to the left. Also there is a hole 15 in the top of the casing communicating with the outer end of the groove 75 11 in the top, so that if desired, the panel can be readily removed from the casing by lifting it vertically so that the upper pivot pin 14 will extend upward through the hole 15 and thus enable the lower pivot to escape over the front flange 12 and then by lowering the panel, it will be separated from the cabinet or casing. And by reversing this 80 operation, the panel can be inserted into the casing.

On each side of each panel 13, as shown 85 in Fig. 3, there is a pair of oppositely disposed vertically extending guides 16, one near each lateral edge of the panel. The lower end of each guide is, however, closed, as indicated by dotted lines in Fig. 2. Card 90 holding strips 17 made of spring metal and narrow are placed transversely in said guides by means of end plates 18 secured to the ends of the strip 17 of sufficient thickness to fit in the guides, but loose enough to 95 be moved up and down readily. The plates 18 are thicker than the strip 17 so as to leave a space between the strip and the panel to receive cards suspended from a strip above. These card holding strips can 100 be inserted or removed, as shown in Fig. 3, where one of them is shown curved in the process of being inserted or removed. When the strip is straightened back into place, as shown on the other side of the panel 13 in Fig. 3, it will extend parallel with the panel and close to it. As seen in Fig. 2, the end plates 18 are wider vertically than the cross

strips 17 and they rest upon each other in series, the plates 18 of the lower strip resting on the bottom of the guides and the plates 18 of each strip 17 rest upon the 5 plates of the lower strip, as shown. This spaces said strips 17 at the right distance apart. Each strip 17 has a hook or pin 19 on it whereby a card 20 is hung. The number of pins 19 for each card may be as desired. But when the cards are hung in place, they overlap each other, as shown in Fig. 2, with a sufficient portion of each card 10 projecting above the next lower card so as to show the desired indicating data for identifying the card while the mass of reading material on the card will extend behind the next lower card and be obscured thereby. However, any card can be removed 15 without disturbing any of the other cards, by merely slipping it off its pin and lifting it vertically. The width of the cards is slightly less than the distance between each 20 pair of guides 16.

From the foregoing, it is seen that in 25 compact form a very large number of record cards may be filed and in such a fashion as to disclose identifying data on each one to make the same readily accessible. There will be one series of cards on each side of 30 each panel 13 and since the cards fit flat against the sides of the panel, each panel with its series of cards will be very narrow and not occupy much space in the cabinet.

Copies of this patent may be obtained for five cents each, by addressing the "Commissioner of Patents, Washington, D. C."

That enables the grooves in the panels to be made close together whereby a large number of panels may be placed in a small cabinet. 35

The invention claimed is:

1. A filing cabinet including a casing, vertically disposed panels movable edge-wise 40 into and out of said casing, a pair of vertical parallel guides on the side of each panel, transverse strips made of resilient material and having widened plates at their ends insertible in said guides so that the 45 end plates will rest upon each other, and an outwardly projecting pin on said strip on which the record card or the like may be hung.

2. A filing cabinet including a casing, vertically disposed panels movable edge-wise 50 into and out of said casing, a pair of vertical parallel guides on the side of each panel, transverse strips made of resilient material and having widened plates at their ends insertible in said guides so that the 55 end plates will rest upon each other and said plates being thicker than said strips so as to leave a space between the strips and the panel to receive cards suspended from strips above, and a pin on said strip for suspending a record card or the like. 60

In witness whereof, I have hereunto affixed my signature.

ERNEST E. DE BURGER.
